UNITED STATES PATENT OFFICE.

CARL AUGUST MÜLLER, OF WITZENHAUSEN, WERRA, GERMANY.

SAFETY LOCK.

Application filed March 9, 1921. Serial No. 450,895.

To all whom it may concern:

Be it known that I, CARL AUGUST MÜLLER, a citizen of the German Republic, and residing at Witzenhausen, Werra, Germany, have invented certain new and useful Improvements in Safety Locks, of which the following is a specification.

This invention relates to locks with chub-like tumblers, which have two or more key sweeps. The hitherto known locks, having tumblers with two such key sweeps, could not be operated through one and the same key-hole, a separate key-hole being required for each group of such key sweeps. Furthermore, locks are known, which have two groups of tumblers, adapted to be adjusted successively through the two tongues or bits of a double-tongue key.

The present invention has for its object to operate tumblers, which are provided with two or more of such key sweeps, through one and the same key-hole. Said tumblers may be provided in the lock in one group or in two groups. The variability need not be reduced even with locks closing from either side, as is the case with the known chub-lock. Thus by obtaining the possibility, when operating the tumblers, of displacing the latter together with the locking-bolt in such a way that the key sweeps used for said operation are then located within the lock beyond reach from the key-hole, the efficiency of the lock is considerably increased. Furthermore, there exists the possibility of ample variations as the single key sweeps as well as the adaptation of the key to the single groups of the latter may be various. Safety-locks constructed according to the invention may be fitted to suit locks requiring two or more turns of the key and having three and more key sweeps for their operation from one side as well as from either side.

In the accompanying drawing:

Figs. 1 and 2 are respectively a front view and a cross-section, of one form of lock,

Figs. 3 and 4 are similar views, to the former, of another form of lock,

Figs. 5 and 6 are similar views, to the former, of a third form of lock, while

Fig. 7 shows a key used.

Figs. 8 and 9 are respectively a front view and cross section, of a lock requiring two turns of the key and having one group of tumblers,

Figs. 10 and 11 are similar views, to Figs.

8 and 9, of a lock with two groups of tumblers,

Figs. 12 and 13 are similar views, to Figs. 8 and 9, of a lock requiring two turns of the key and adapted to be operated from either side.

Referring to Figs. 1 and 2, which show a lock to be operated from one side:—On the locking bolt *a* a plurality of tumblers *b* are vertically movable and adapted to engage with slots *c* over pins *d* on said bolt. Said tumblers are pressed downwards by springs *h* bearing upon pins *i* on said bolt, and they engage with openings *e* over the arresting-pin *f* on the lock casing. The tumblers have two groups *x* and *y* of key sweeps, said groups being arranged one behind the other. The bolt *a* has corresponding sweeps for the key. The key, which for instance may be hollow and inserted over the pin *g*, has two tongues or bits of known type, as shown in the drawing by dotted lines. During its operation, it lifts first with its one tongue the tumblers at the key sweeps *x* and disengages them from the arresting-pin *f*, while it shifts the locking-bolt, until the latter is again arrested. As the tumblers have moved with the locking-bolt, upon a further turning of the key the second tongue of the latter arrives below the second group of key sweeps *y* on the tumblers, and said second tongue serves then for adjusting the key sweeps *y* when re-opening the lock. As the two groups *x* and *y* of key sweeps may be of variable design, as well as the two tongues of the key, it is obvious that a great variability and thus an increased efficiency is ensured. The order of succession of the first group at *x* may be totally different to that of the second group at *y*. Of course, instead of a double-tongue key, also two different keys with one tongue each may be used successively for operating the lock, one key being adapted to suit the group *x* and the other the group *y*. Thereby, a control of the lock is possible by two persons having each one key, while using one and the same keyhole. The guiding of the tumblers may be of any type, and instead of blade springs as shown spiral springs or the like may be used.

Furthermore, for increasing the efficiency, two groups of tumblers may be employed, as shown in Figs. 3 and 4. The second group, which is the lower one in the drawing, also moves with the bolt. In case of

four groups of key sweeps being formed of a different stroke, a key with two double-tongues is used, each shaft end of the key having a double-tongue (Fig. 7). One 5 double-tongue acts then on the groups x and z of the tumblers, while for re-opening the other double-tongue is applied to the groups y and w . Of course, also two different keys having each one double-tongue may be employed. The locking-bolt has always key sweeps at the upper arm only as shown in dotted lines.

The key sweeps may be identical in opposite alternate groups, that is they may 15 have equal order of succession; thus, the groups x and w , and the groups y and z , are identical. In this case, one double-tongue key only need be used.

In the example first described and shown 20 in Figs. 1 and 2, the groups of key sweeps x and y may also be identical, one key with one tongue being then sufficient for their operation.

For keys locking from either side, for 25 each pair of groups of key sweeps a separate keyhole must be arranged, one in the cover of the lock for the right-hand groups x and z (Figs. 5 and 6) and the other in the opposite wall of the lock for the left-hand 30 groups y and w . The lock is a one-turn lock, and one and the same double-tongue key closes the lock from the right on pin g^1 (Fig. 5) at the groups x and z and from the left on pin g^2 at the groups y and w . 35 The tumblers are here so arranged that they do not participate in the movement of the bolt. For instance, the tumblers may be guided on pins d arranged on the lock cover while the arresting contrivance f is arranged on the bolt.

In a similar way, with locks closing from 40 either side, such as for instance shown in Figs. 5 and 6, the two left-hand groups of sweeps y and w may have an opposite order of succession to that of the right-hand groups x and z . The lock is then operated by means of a double-tongue key, which is 45 designed corresponding to the two opposite groups x and z . If, for instance, all the four groups of key sweeps are differently shaped, the lock is operated by means of two double-tongue keys or by one double-tongue key 50 having a double-tongue on each end.

Thus, as is obvious from these examples, 55 the groups of key sweeps may be variously arranged: as to the single groups by themselves as well as to the proportion of the single groups to the other groups. Single-tongue and double-tongue keys and keys 60 with quadruple-tongue may be employed.

Figs. 8 to 13 inclusive show modifications having more than two key sweeps. Identical reference letters designate identical parts, as in Figs. 1 to 6 inclusive.

65 In the example shown in Figs. 8 and 9, in

which also any number of tumblers b may be combined in one group, three key sweeps x , y , z are arranged beside each other. The double-tongue key to be inserted over pin g and indicated by dotted lines, shifts at the 70 same time bolt and tumblers, while one sweep after the other comes within reach of the keyhole, the key sweeps not attacked by the key lying in covered position within the lock beyond reach from the keyhole. The 75 single sweeps are, with a single-tongue key, identical and, with a double-tongue key, different in such a way that the first key sweeps x agree again with the last ones z .

With locks having two groups of tumblers, such as shown in Figs. 10 and 11, which are operated from one side through the same keyhole and by means of one and the same double-tongue key, the single key sweeps of the two groups of tumblers may 80 have an order of succession, analogous to the construction shown in Figs. 8 and 9, in such a way that the first groups of said key sweeps have another order of succession as 85 the second ones, and the third groups agree with the first groups, so that the lock is to be operated by two turns of a key with a two double-tongues, of which one corresponds to the first and the other to the second opposite group of key sweeps. The 90 groups of key sweeps may also agree with each other in their order of succession in crosslike fashion, so that the two first groups correspond to one another and the third pair of key sweeps again to the first 95 pair.

With locks closing from either side, such as shown in Figs. 12 and 13, a further number of key sweeps, corresponding to the plurality of key sweeps to be adjusted through 105 the keyhole on one side of the lock, are arranged on the same group of tumblers and adapted to be operated through a keyhole on the other side of the lock not coinciding with the first keyhole.

With a one-turn lock closing from either side, each group of tumblers is provided with four key sweeps 1, 2, 3 and 4 (Fig. 12) for the key. With a two-turn lock closing from either side, each group of tumblers 110 has six key sweeps for the key.

As, with all said tumblers, one spring acts on either side of the same, they follow the operation of the key from all sides, and it is obvious that also the arrangement of the 120 key sweeps serving for the operation from one side and of those serving for the operation from the other side may be symmetrical relatively to the arresting groove or to the opening in the tumbler.

125 What I claim, is:

1. The combination with a safety lock having a multiple turn, key-operated bolt and a single key-hole, of key-operated tumblers for locking said bolt in each stage of 130

its movement, said tumblers having key sweeps arranged in different groups for the different stages of bolt movement, one of said groups adapted to move opposite the 5 keyhole after each key operation of the bolt for operation by its particular key-tongue, substantially as set forth.

2. The combination with a safety-lock having a single key-hole, of key-operated 10 tumblers therein having a plurality of key sweeps arranged in different groups, one of said groups adapted to register with the key-hole on complete projection of the bolt so as to be in operative position for the retraction 15 of said bolt, substantially as set forth.

3. A safety-lock as specified in claim 1, in which said tumblers are arranged in opposite groups, substantially as set forth.

4. A safety-lock as specified in claim 1,

having alternately varying and equal key 20 sweeps on one group of tumblers, the first group of sweeps corresponding to the third, and the second to the fourth group, substantially as set forth.

5. A safety-lock as specified in claim 1, 25 having two oppositely arranged groups of tumblers, varying key sweeps on one and the same group of tumblers arranged side by side, and identical opposite alternate sweeps in the opposed groups of tumblers, 30 substantially as set forth.

In testimony whereof I have hereunto set my hand in the presence of two subscribing witnesses.

CARL AUGUST MÜLLER.
